UNITED STATES PATENT OFFICE

BUREN L. CORLEY, OF SAN FRANCISCO, CALIFORNIA

APPLIANCE FOR TREATMENT OF DISEASES

Application filed July 11, 1928. Serial No. 291,879.

The present invention relates to an apparatus or appliance for use in the treatment of disease.

It is the practice to treat certain diseases by dia-thermy and sinusoidal, and in the treatment of diseases of the male organs crude apparatus has been heretofore employed rendering the treatment both tiresome, tedious and unpleasant to the patient.

By the present invention, I provide a modern, practical and simple apparatus for dia-thermically treating diseases of the male organs, which apparatus when in use enables the patient to assume a comfortable, natural position.

The invention provides a fluid containing receptacle for receiving the organ to be treated; the receptacle adapted for removal from the apparatus or of adjustment therein to be held in the position most convenient for use by the patient. The invention further provides for the connection of the receptacle with a suitable conductor to afford an electric current leading to the member to be treated, and the connection of a secondary fluid containing receptacle with a conductor ensuring the completion of the circuit through the patient, when seated in the chair, and portions of the body received within the respective receptacles.

The invention has the further object of being adaptable for conversion, when not in use, into a chair for universal service.

With the above mentioned and other objects in view, the invention consists in the novel construction and combination of parts hereinafter described, illustrated in the accompanying drawings and pointed out in the claims hereto appended; it being understood that various changes in the form, proportion, size and minor details of construction within the scope of the claims may be resorted to without departing from the spirit or sacrificing any of the advantages of the invention.

To more clearly comprehend the invention, reference is directed to the accompanying drawings, wherein—

Fig. 1 is a view in side elevation of one embodiment of my invention.

Fig. 2 is a view in front elevation.

Fig. 3 is a view in longitudinal section through the chair seat, illustrating the receptacle within its receiving aperture in the chair seat, the means for holding the receptacle in its adjusted position, and the electrical connection with the interior of the receptacle.

Fig. 4 is a similar view through the chair seat with the receptacle receiving aperture closed by a properly shaped and fitting closure.

Fig. 5 is an inverted view of the chair seat, illustrating the means for retaining the receptacle in its adjusted position in the chair seat opening.

1 indicates a chair having legs 2, a seat 3, back 4 and arms 5. Hinged to the side edges of the seat at 6 are the leaf extensions 7 carrying on their upper surfaces the contact plates 8, from which extend conductors 9, terminating in conductor sockets 10, with which is adapted for detachable connection one conductor 10' of an electric circuit.

Any suitable means of well known type may be employed for releasably holding the leaves in their horizontal position, and to retain the leaves in their folded position, headed members 11 are mounted on the under-side of each shelf and engage with yieldable catch means 12 on the chair legs, as in Fig. 2.

The surface of the seat is provided with a suitable insulating cushion or fabric 13 and in its longitudinal center, near its forward edge, is provided with a circular aperture 14, the walls of which slope forwardly and downwardly, as in Figs. 3 and 4. The aperture is formed preferably by cutting a single piece 15 from the seat, which is adapted for insertion into the aperture, as in Fig. 4, when it is desired to close the same and use the chair for general purposes.

Beneath the seat 3 and embracing the edges of the aperture 14 are the pivotally mounted clamping arms 16 adapted when drawn together by the action of a spring 17 to tightly grip a receptacle 18 positioned within the aperture 14 therebetween. The receptacle 18 is of non-conducting material, its walls 100

flare toward its open mouth and it is provided through the center of its bottom with an aperture. Through the aperture extends an electric terminal screw 20 insulated at 21 5 from the receptacle, and carrying on its inner end a disk 22 within the base of the receptacle. The disk is of a diameter less than that of the interior of the receptacle and is spaced from the bottom affording a fluid 10 circulation therearound.

The receptacle is inserted into the aperture 14 through the upper open end of the aperture 14 with the base of the receptacle downwardly disposed and projecting 15 through the aperture with the receptacle inclined toward the rear of the chair.

When in position, the receptacle 18, gripped by the arms 16, is held in its desired position of adjustment.

20 With the binding post portion of the screw 20 is connected the other conductor 23 of an electric circuit, the conductor connecting through a plug 24 with which is connected a conductor 25.

25 It will be observed that the chair is a portable structure, is adapted for a special use or may be used as chairs are generally.

When in use, the plug 15 is removed from the seat and the receptacle is inserted, as 30 illustrated, with the conductor 23 connected. One of the leaves 7 is raised and a pan or tray 26 is positioned on the contact plate 8 thereof. With suitable medicament in the receptacle and with fluid in the pan or tray 35 26, the patient is seated in the chair with the male organ to be treated inserted into the fluid within the receptacle and one hand in the pan or tray 26 completing an electric circuit through the patient, the position of the 40 patient insuring the circuit travelling through the member to be treated and the circuit passing through the medicament maintaining the same heated.

The circuit may be completed through one 45 of the shelf trays and a conductor gripping the body, in the practise of a sinusoidal or dia-thermy treatment; or through either the receptacle or one of the trays and a body gripping contact; or through two trays with 50 the circuit completed through the trays by separate leads, or through one of the shelf trays and a tray associated with the pedal extremities of the body.

I claim:—

55 1. A medical appliance comprising a chair provided with an apertured seat, a receptacle positioned within the seat with this mouth upwardly disposed, a second receptacle, electric conductors connected with said receptacles, said receptacles containing fluid for receiving parts of the body of the patient to be treated when seated in said chair.

60 2. A medical appliance comprising a chair provided with an apertured seat, a receptacle positioned within the seat aperture

70 with its mouth upwardly disposed, means embracing the seat aperture for holding the receptacle in its adjusted position, a supporting shelf associated with the chair, a second receptacle resting on the shelf, electric conductors connected with and extending from said receptacles, said receptacles containing fluid for receiving parts of the body of the patient to be treated when seated in said chair.

75 3. A medical appliance comprising a chair provided with an apertured seat, a receptacle positioned within the seat aperture with its mouth upwardly disposed and with the body of the receptacle inclined toward the rear of the seat, means for adjustably retaining the receptacle in position within said aperture, a hinged shelf associated with the seat, a second receptacle carried by the shelf, electric conductors connected with and extended from said receptacles, said receptacles containing fluid for receiving parts of the body of the patient to be treated when seated in said chair.

80 In testimony whereof I have signed my name to this specification.
